GRILLE BAR FOR AN AUTOMOBILE

Alfred E. Niksa, Royal Oak, Mich., assignor to Chrysler Corporation, Highland Park, Mich., a corporation of Delaware

Application June 24, 1953, Serial No. 25,640

Term of patent 7 years

(Cl. D14—18)

To all whom it may concern:

Be it known that I, Alfred E. Niksa, a citizen of the United States, residing in the city of Royal Oak, county of Oakland, and State of Michigan, have invented a new, original, and ornamental Design for a Grille Bar for an Automobile, of which the following is a specification, reference being had to the accompanying drawings, forming part thereof, in which:

Fig. 1 is a front elevational view on a reduced scale of a grille bar for an automobile, showing my new design;

Fig. 2 is a fragmentary front elevational view of a portion of the grille bar illustrated in Fig. 1 shown on a larger scale;

Fig. 3 is a fragmentary plan view of the portion of a grille bar illustrated in Fig. 2;

Fig. 4 is a side elevational view thereof;

Figs. 5, 6, 7 and 8 are sectional views taken on the lines 5-5, 6-6, 7-7 and 8-8, respectively, of Fig. 2; and

Fig. 9 is a front perspective view thereof on a reduced scale.

The broken line showing in the drawing figures is for illustrative purposes only.

I claim:

The ornamental design for a grille bar for an automobile, substantially as shown and described.
